BINDING AND HANDLE-ATTACHING TAPE FOR PACKAGES.

1,160,878.

Specification of Letters Patent.

Patented Nov. 16, 1915.

Application filed August 19, 1914. Serial No. 857,523.

To all whom it may concern:

Be it known that we, SHEPARD J. GOLDBERG and AARON MENDELSON, citizens of the United States, and residents of the city of New York, borough of Brooklyn, in the county of Kings and State of New York, have invented a new and Improved Binding and Handle-Attaching Tape for Packages, of which the following is a full, clear, and 10 exact description.

This invention has special reference to package tying and carrying devices and more especially to improved binding and handle attaching tape therefor.

The main object of the invention is to eliminate the use of cord or other package fastening devices necessitating knotting of the cord or the provision of expensive metallic parts for anchoring the ends of the cord 15 or tying material and also to avoid the objections to ordinary adhesive strip paper commonly used for fastening a wrapper on a package, by providing a combined binding and handle attaching tape which is provided 20 with adhesive for applying or securing the same to the package and at spaced points with handle engaging portions or loops for the convenient engagement of the hook ends of a novel handle in such a manner that 25 movement of the handle on the tape is prevented and the objection heretofore encountered by the attachment of a handle to a binding cord overcome.

With the above and other objects in view, the invention resides in the peculiar combination and arrangement of parts to be hereinafter more fully described, illustrated and claimed, it being also an object to provide a device which is simple in construction, durable and efficient.

Reference is to be had to the accompanying drawings forming a part of this specification, in which similar characters of reference indicate corresponding parts in all the 40 views, and in which—

Figure 1 is a perspective view of a fragmentary portion of a package bound with one form of the improved tape and a novel handle attached thereto; Fig. 2 is an enlarged plan view of a portion of the tape; Fig. 3 is a longitudinal sectional view taken on the line 3—3 of Fig. 2; Fig. 4 is a cross sectional view taken on the line 4—4 of Fig. 2; Fig. 5 is an under side view of the form 50 of tape or strip shown in Fig. 2; Fig. 6 is a fragmentary plan view similar to Fig. 2 and

showing a modified form of strip or tape; Fig. 7 is a longitudinal sectional view taken on the line 7—7 of Fig. 6; Fig. 8 is a cross sectional view taken on the line 8—8 of Fig. 6; Fig. 9 is a plan view of a further modified form of tape; Fig. 10 is a cross sectional view taken on the line 10—10 of Fig. 9; Fig. 11 is a cross sectional view of a still further modified form of tape; Fig. 12 is an under side view of another form of the invention; and Fig. 13 is a perspective view of a modified form of handle from that shown in Fig. 1.

At present it is common to tie packages with cord after the same are wrapped with paper and it is necessary to knot the cord so as to bind the package. In addition, handles having hooked ends are engaged under a straight strand of cord or binding string so as to permit convenient carrying of the package, but objection is had to this method of attaching the handle owing to the fact that the handle will slip or be displaced longitudinally on the cord with the result that the package is unbalanced in such a manner that the cord or twine becomes displaced and oftentimes the handle from the cord or twine. With the use of an ordinary adhesive strip used for fastening a wrapper on a package or sealing a package or box it is impossible to attach a handle and the strip not being reinforced is likely to break so that the purpose for which it is designed is not fulfilled. The present invention aims to overcome these objections by providing a tape or binding strip provided with spaced handle engaging portions to permit convenient and proper attachment of a handle in such a manner that the package will be balanced, as well as to provide for the attachment of the tape or strip by an adhesive coating without the necessity of tying knots but so reinforcing the strip or tape that the same will not be likely to break.

In carrying our invention into practice as illustrated by the accompanying drawings, the numeral 10 designates a package wrapped in any suitable way and bound by one form of the strip or tape indicated by the numeral 11 and specifically shown in Figs. 2 to 5 inclusive. This form of the tape is made up of two strips 12 and 13 of paper or other suitable material to give the proper strength, said paper being oiled or otherwise treated and the two strips being secured together intermediately by adhesive. The strip

13 is made imperforate but the strip 12 is provided at spaced points equi-distantly located with spaced transverse cuts or slits 14 terminating at spaced parts from the edges of the strip to receive a reinforcing and handle attaching ribbon, tape or other suitable strip 15, it being preferred that the strips 12 and 13 be of paper and the strip 15 of ribbon or cloth tape so as to reinforce the paper and simultaneously provide for the attachment of a handle.

The tape or ribbon 15 is positioned between the strips 12 and 13 and threaded through the cuts 14 so that portions of the tape are exposed between the spaced pairs of cuts. In this manner when the package is bound with the tape as shown in Fig. 1, portions of the tape between the cuts produce loops 16 designed for engagement by the hook extremity 17' of a handle 17 comprising a section of sheet metal having its upper end split and bent to provide oppositely extending and downwardly curved grasping portions 18. The hook portion 17' is provided with a downwardly and inwardly bent resilient tongue 18' stamped therefrom, beneath which the tape engages and is held from displacement. The tape can be applied to the package by an adhesive coating 19 applied to the inner side of the strip 13 so that it is unnecessary to tie the tape and it is only necessary that the strip to which the handle is attached be so secured to the package that one of the loops 16 will be substantially equi-distantly spaced from the ends of the package so that the latter will be balanced when the handle is applied.

In the form of the invention shown in Figs. 6, 7 and 8 of the drawings the tape is made up of two strips of paper 20 and 21 with the strip 21 coated on its under surface as heretofore described and shown at 19 in Fig. 5 of the drawings, while the strip 20 is provided at spaced intervals with longitudinal openings or slots 22 adapted to expose spaced portions of a reinforcing cord or twine 23 which is run between the strips and held in position due to the latter being secured together by adhesive. Loops 24 are thus provided by the exposed portions of the cord or twine for engagement by the handle in the manner heretofore described.

In Figs. 9 and 10 of the drawings the tape is shown made up of a single strip 25 folded longitudinally intermediate its width, as shown at 26, to provide top and bottom portions 27 and 28 having spaced cuts or slits 29 so that a section of ribbon or tape 30 fastened between the folded parts of the strip by adhesive can be interlaced with respect to the spaced transverse cuts or elongated apertures so as to provide handle attaching loops 31 for the same purpose heretofore referred to.

In Fig. 11 of the drawings another modi-

fication is shown in which a single strip 32 is covered with adhesive on the inner face of the bottom part 33 and the foldable edge portion 34 so that by folding the opposite side or edge portion 35 on the part 33 the two may be secured together and the part 34 then folded over the part 35 to close both edges of the tape or strip and leave no edges exposed. In this form of the invention the strip is reinforced by a cord 24 as heretofore described in connection with Figs. 6, 7 and 8 to reinforce the strip and provide for the attachment of the handle to a bound package.

In Fig. 12 a strip 36 is also provided with spaced handle-engaging portions, the strip in this instance being provided at spaced points with adhesive coatings or portions 37 so that the intermediate portions 38 which are un-coated will be free from the package when the portions 37 are moistened and caused to adhere thereto so that the hooks of the handle, such as shown or any other of the ordinary handles employed in the merchandise trade, can be engaged beneath the spaced handle-engaging portions or loops 36 whereby the package is both bound and provided with means for conveniently carrying or transporting the same.

In Fig. 13 of the drawings a handle 39 of modified form is shown, the same being made of wire rebent intermediate its ends to provide a shank portion, the lower bight portion of which is bent up to provide a hook 40 and then downwardly and inwardly to provide a resilient tongue 41 for the same purpose as the tongue 18', as shown in Fig. 1 of the drawings. The upper ends or extremities of the section of wire or metal are curved outwardly and downwardly to provide grasping portions 42.

Having thus described our invention, what we claim as new and desire to secure by Letters Patent is:—

1. A binding and handle attaching tape for packages, comprising a pliable strip-like element having spaced loops lying within the edges of the element and projecting from a face thereof.

2. A binding and handle attaching tape for packages having means to attach the same to a package and means to provide spaced handle engaging members, both of said means being non-metallic and pliable.

3. A binding and handle attaching tape for packages having means to attach the same to a package, and reinforcing means for the tape provided with spaced handle engaging portions.

4. A binding and handle attaching tape for packages having means to attach the same to a package, and reinforcing means for the tape, said reinforcing means being embedded in the tape and forming the spaced handle engaging portions.

5. The combination with a package suit-

ably wrapped; of a binding and handle attaching strip having an adhesive coating for securing the same to a package to obviate tying and provided with spaced handle engaging portions, and a handle to coöperate with said handle engaging portions whereby the handle is held from movement.

6. A binding and handle attaching tape, comprising a strip having top and bottom portions and a reinforcing member between said portions with spaced exposed handle attaching parts.

7. A tape comprising a fabric reinforcing member and paper coverings secured to-

gether to inclose said reinforcing member, 15 one of said coverings having openings through which the reinforcing member extends to produce spaced loops as and for the purpose described.

In testimony whereof we have signed our 20 names to this specification in the presence of two subscribing witnesses.
